UNITED STATES PATENT OFFICE.

JOSEPH ANDERSON, OF NEW YORK, N. Y.

TICKET-DEPOSIT BOX.

1,080,404.

Specification of Letters Patent.

Patented Dec. 2, 1913.

Application filed September 6, 1911. Serial No. 647,890.

To all whom it may concern:

Be it known that I, JOSEPH ANDERSON, a citizen of the United States, and a resident of the city of New York, Ridgewood, borough of Queens, in the county of Queens and State of New York, have invented a new and Improved Ticket-Deposit Box, of which the following is a full, clear, and exact description.

10 Among the principal objects which the present invention has in view are: to provide means for canceling, exhibiting and depositing tickets mechanically and outside of the control of the attendant; to provide 15 means for preventing the extracting of tickets from the deposit box after being placed therein; and to provide a mechanism for operating the canceling and depositing devices which is simple, efficient and durable in construction.

20 One embodiment of the present invention is disclosed in the structure illustrated in the accompanying drawings, in which like characters of reference denote corresponding 25 parts in all the views, and in which—

Figure 1 is a vertical longitudinal section of a ticket deposit box constructed and arranged in accordance with the present invention, the section being taken on the line 1—1 in Fig. 2; Fig. 2 is a vertical cross section taken on the line 2—2 in Fig. 1; Fig. 3 is a detail view, on an enlarged scale and in side elevation, of the driving and locking devices for the exhibiting tray; Fig. 4 is a 35 side view of the construction shown in Fig. 3.

As seen in the accompanying drawings, the rolls 12, 12 are provided with curved or knurled surfaces adapted to indelibly punch or press the tickets when placed between the 40 said rolls. The tickets are guided to the rolls by a hopper 13. The tickets after passing the rolls 12 are delivered to a second hopper 21 and deposited thereby on the then horizontally disposed blades 14. The blades 14 are mounted in the disk heads 15, the grooves 45 for said blades being set in the said heads and in perpendicular arrangement. The operating mechanism for the rolls 12 on the disk heads 15 is such that the said heads are 50 rotated at intervals, and at the end of each rotation are disposed in position so that two of the said blades are in horizontal arrangement.

The driving shafts 18 and 19 of the rolls 55 12 are mounted in bearings at the upper part of the spider frame 16. The frame 16, at

the lower end, furnishes bearings for the pintles 17 of the disk heads 15. As seen in Fig. 2 of the drawings there are two sets of disk heads 15 and pintles 17 therefor. The disk heads and pintles are operatively connected by gear wheels 20, the teeth whereof are in mesh. When the said heads and blades carried thereby are disposed as shown in Fig. 2 of the drawings, the horizontal blades 60 on the meeting side of the two sets of disks form conjointly a platform or tray on which the tickets are deposited for inspection of the customer or attendant. The tickets are prevented from passing through the space 65 between the edges of the juxtaposed blades by the rod 22, as shown in Fig. 2. The rod 22 is placed directly above the opening between the juxtaposed blades 14, and operated to deflect any ticket which would drop 70 from the opening between the rolls 12 in the path of the opening between the said juxtaposed blades 14.

The rolls 12 are provided with transmission gear wheels 23 whereby there is imparted to the said rolls a relatively even rotation. The shaft 18, as seen in Fig. 2 of the drawings, is set in the frame 16. The shaft 19 is mounted in sliding boxes 24. The boxes 24 are normally moved by the springs 80 25 to press the rolls 12 together. The teeth of the wheels 23 are sufficiently long to avoid disengagement. Between the shaft 18 and one of the pintles 17 is provided a transmission mechanism arranged in such manner 85 that the disk heads 15 are rotated at stated intervals one-quarter turn, the intervals being measured by the rotation of the shaft 18. That is to say, the shaft 18 may be set to rotate four, or any number, of complete 90 turns, in the interval between the engagement of the disk head 15 and partial rotation of the same.

The transmission mechanism above referred to consists primarily of the paired 100 bevel gear wheels 26 and 27. The wheel 26 is fixedly mounted on the shaft 18. The wheel 27 is similarly mounted on the shaft 28. The shaft 28 is suitably mounted in bearings formed in the arm 29, which arm 105 also forms one of the bearings for the short shaft 30 provided for the bevel gear wheel 31. The gear wheel 31 is driven by the bevel pinion 32 which is fixedly mounted upon the shaft 28. The ratio between the 110 pinion 32 and wheel 31 is that which governs the number of rotations of the shaft 18 and

rolls 12 connected therewith relative to the rotation of the wheel 31. The wheel 31 is provided with a pin 33 extended from the inner face thereof. The pin 33 extends into the slots 34 of the disk 35, as seen best in Fig. 5 of the drawings, the pin 33 being shown in dotted lines therein. The arc of movement of the pin 33 while in engagement with one of the slots 34 is such as to move the disk 35 one-quarter of a complete rotation. The disk 35 is rigidly mounted upon one of the pintles 17 extended from one of the disk heads 15. As seen best in Figs. 1 and 2 of the drawings the one-quarter rotation of the disk heads 15 disposes the blades 14 in such manner as to present a flat tray-like arrangement of the two inner and horizontally disposed blades 14.

Extended through the frame 16 and through the perforation provided therefor, is a plunger 36, the function of which is to bear upon the wheel 20 to arrest and hold the same immediately the pin 33 has passed out of engagement with any one of the slots 34. The plunger 36 operates as a brake upon the wheel 20 and serves to hold relatively rigid the heads 15 and blades 14 mounted thereon. The plunger 36 is provided with a spring which normally draws the said plunger outward from the wheel 20 to press against the face of the wheel 31. In the path of the plunger 36 on the wheel 31, is provided a cam-shaped recess 37. See Fig. 4 of the drawings. As the pin 33 enters any one of the slots 34 the recess 37 receives the plunger 36, the spring provided therefor drawing the same away from the wheel 20. This operation at the critical moment releases the wheel 20 and parts connected therewith to be rotated readily by the pin 33 and disk 35. The rotation of the disk heads 15 and blades 14 serves to drop any tickets which have accumulated upon the horizontally disposed blades 14 into the receptacle 38 of the ticket box.

The mechanism described is driven by any suitable form of prime mover. The electric motor 39 shown in Fig. 1 of the drawings is that which is preferred by me. The armature shaft of the motor is connected by means of the transmission gear wheels 40 and 41. The gear wheel 40 is fixedly mounted on the shaft 18. When the motor 39 is driven the shaft 18 and parts connected therewith are operated. While I have herein described the use of the electric motor and a particular form of transmission gear wheels operatively connecting the same with the shaft 18, it will be understood that I do not confine myself to the use of this particular form of motor or of transmission. Under usual conditions the motor 39 continuously drives the rolls 12 and intermittently the disk heads 15.

In the operation of ticket receiving the

ticket is dropped into the hopper 13 to be caught by the rolls 12 and serrated or punched thereby and delivered upon the two blades 14, 14 which at that time happen to be in the horizontal position. At the interval designed the disk heads 15 and blades 14 carried thereby are rotated to precipitate the tickets into the box or permanent receptacle provided beneath the disk heads 15 and blades 14. By this operation it is taken out of the power of the attendant to permit the tickets to accumulate in the box or to extract the same therefrom upward through the hopper 13. In this he is prevented by the continuous operation of the rolls 12 and by the operation of the disk heads 15 which at short intervals pass the comparatively slight accumulation of tickets from the tray formed by the blades 14 into the strong box or receptacle 38. As shown in Fig. 1 of the drawings, there is provided for temporary use a crank handle 42, which operating through a floating clutch 43 engages a fixed clutch 44, being pressed into engagement therewith by a spiral spring 45. The teeth of the floating and fixed clutches 43 and 44 are ratchet-shaped to engage when the crank handle 42 is rotated in one direction only. This provides against rotating the shaft 18 backward.

The hopper 13 is preferably made from glass and is supported in the upper frame or box 46. The hopper 21 is likewise made from one piece of glass and is supported in a bracket frame 47 formed in the spider frame 16. The blades 14 are preferably constructed from glass. The long sides 48, 48 of the hopper box are also preferably constructed from glass. In this manner the tickets are exposed to view of both the depositor and the attendant until precipitated from the blades 14 within the receptacle 38.

By means of suitable frames 49 the glass parts are bound together. The upper structure comprising the hopper 13, sides 48, box 46 and sign 50, is suitably mounted in the top 51 of the receptacle 38. To mount the box 46 on the receptacle 38 the top 51 is provided with sockets 52 to receive the dowels 53. The dowels 53 and sockets 52 form registering guide members for the mounting of the box 46 and the receptacle 38. Any suitable key operated lock may be employed for securing the box 46 in position after the dowels 53 have been inserted in the sockets 52 in the manner shown.

By constructing the hoppers 13 and 21 from solid glass the machine is protected against robbery by the usual method, which is to force the jaws of the hopper to permit the introduction of a suitable tool past the canceling rolls 12 or present chopping mechanism. When using the hoppers 13 and 21 any effort of the character mentioned

would result in breaking or otherwise destroying the said hoppers, and thus operate effectively as a detector on the attendant.

Having thus described my invention, what I claim as new and desire to secure by Letters Patent is:—

1. A ticket box, having canceling rolls; an adjustable tray; and a driving mechanism for continuously rotating said rolls and for dumping said tray at fixed intervals, the operation of said means being uncontrollable by the attendant.

2. A ticket box, having canceling rolls; an adjustable tray; a driving mechanism for

continuously rotating said rolls and for dumping said tray at fixed intervals, the operation of said means being uncontrollable by the attendant; and transmission members interposed between said tray and said driving mechanism, for accelerating the movement of said tray.

In testimony whereof I have signed my name to this specification in the presence of two subscribing witnesses.

JOSEPH ANDERSON.
